INCINERATING APPARATUS

Charles W. Nichols, West Orange, N. J., assignor
to Nichols Engineering & Research Corpora-
tion, New York, N. Y., a corporation of Delaware

Application May 29, 1940, Serial No. 337,747

3 Claims. (Cl. 110—13)

This invention relates to furnace apparatus for incinerating waste material such for example as municipal waste including garbage, refuse and trash.

The apparatus of this invention is particularly adaptable for use in relatively small waste disposal plants, for the rapid drying and thorough burning of waste material of highly irregular characteristics with substantially a minimum of expense and labor. Heretofore with relatively small installations for the burning of garbage and trash, etc., it has been generally customary to provide a grate in a simple furnace chamber, the waste material being dumped onto the grate and thereafter stoked by manual labor to the extent necessary to distribute the material over the grate and to allow access of air to various parts thereof from time to time. Such constructions have not only involved a considerable labor expense for frequent or continuous attention by one or more workmen, but the resulting drying and burning action on the grate is too irregular for uniform and thorough combustion. As a result, considerable smoldering occurs with consequent obnoxious odors, and the resulting ash is sometimes mixed with considerable unburned material.

Efforts to avoid these difficulties have in general involved equipment which is too expensive to construct and maintain in dependable condition for use in relatively small plants.

The objects of this invention include the provision of an incinerator for eliminating or substantially minimizing the above noted difficulties by the use of relatively simple, dependable and inexpensive apparatus. Further objects, features and advantages will clearly appear from the detailed description given below taken in connection with the accompanying drawings forming a part of this specification and illustrating by way of example one form of apparatus which may be used in carrying out the invention. The invention consists in such novel features, arrangements and combinations of parts as may be shown and described in connection with the apparatus herein disclosed.

In the drawings, Figs. 1 and 2 respectively are vertical and horizontal sectional views showing a furnace construction embodying the invention in a preferred form;

Fig. 3 is an enlarged vertical sectional view of the hearth portion and accompanying parts of the furnace of Figs. 1 and 2;

55 Figs. 4 and 5 respectively are horizontal sec-

tional views taken substantially along the lines 4—4 and 5—5 of Fig. 3;

Fig. 6 is an enlarged elevational view partially in section along the line 6—6 of Fig. 4;

Fig. 7 is a plan view and Figs. 8 and 9 are elevational views, showing a modified form of the rotatable structure embodying the invention.

In the apparatus as shown in Fig. 1 a furnace chamber 10 is shown surrounded as by cylindrical walls 11 and having an inlet 12 at the middle of its roof through which inlet the waste material to be treated may be introduced. The furnace chamber may be accompanied by a gas combustion chamber as at 13, having a gas outlet 13' and separated from the furnace chamber, except near the top of the furnace, as by a wall 14 forming a part of the cylindrical wall structure of the furnace. The middle portion of the bottom of the furnace may be occupied by a substantially circular fixed central hearth area 15 as shown, surrounded by an annular grate area 16, formed if desired of removable sections as shown. The furnace wall 11 may be provided with several doors as at 17, through which access may be had when desired to the grate areas. Access may be had to the ash pit spaces beneath the grate as through doors as at 18.

The material to be incinerated may be introduced through the opening 12 from time to time in such quantities as to maintain a pile thereof as at 19 covering the central hearth area with the peripheral and dried or partially dried portions of the pile extending out over the annular grate areas upon which areas the material is burned. A rotatable and generally conically shaped hollow member 20 may be mounted at the center of the hearth 15, this member having affixed thereto and rotatable therewith two or more generally tangentially extending arms as at 21, 22 of such shape and character as to gradually advance the material from the central hearth areas onto the grate areas, while at the same time periodically agitating the material in the pile 19 and introducing supplies of air thereto in a manner hereinafter described.

The member 20 may be formed with a hollow rotatable stem 23 mounted at the base of the furnace on a suitable bearing as at 24 and arranged to be constantly rotated as by gearing 25. A conduit 26 is connected with a suitable source of supply of air under some pressure, preferably heated air. This conduit may communicate with a hollow member 27 enclosing suitable bearings for the member 23 and also enclosing a space from which supplies of the air may be intro-

duced through suitable openings as at 28' into the member 23. From the member 23 the air thus supplied travels up into the hollow conical member 20 and thence out into the pile of waste material through numerous apertures as at 29 formed in the surface of the member 20. Also as shown, the arms 21, 22 may be made hollow and in communication with the space within the member 20 whereby other portions of the air supply 10 may pass out through apertures 30 formed along the rear surfaces of the arms 21, 22.

As shown in Figs. 3 and 4, the apertures 29 may be uniformly distributed at least over the upper surface areas of the conical member 20 15 and preferably each of these apertures is directed outwardly, and rearwardly as compared with the direction of rotation of the member 20, whereby the waste material will readily slide by these apertures without tending to enter and 20 block the same against passage of air.

The member 20 may be formed with flat surface areas as at 31 against which the inner ends of the arms 21, 22 are secured. These areas 31 may be formed with openings 32 for bringing the 25 cavity of member 20 into communication with the hollow spaces in the arms. The inner end of each arm may be formed with a generally sector shaped flange portion as at 33 adapted to be adjustably bolted to the areas 31. That is, 30 for example the lower and forward edge of each of the arms 21, 22 may be provided with a longitudinally extending bolt as at 34 having threaded engagement with the area 31 and acting as a pivot axis about which the position of the arm 35 may be adjusted and secured in desired positions as by bolts 35 engaging slot 36. With this arrangement the inclination of the forward surface of each arm as at 37 in respect to the hearth may be adjusted to suit varying operating 40 conditions and at such an angle as to suitably agitate and advance the particular type of waste material being treated. It will be observed that such adjustments will vary the extent to which the rear portions of each arm protrude up into the pile of waste material and thereby vary the 45 extent to which the waste material is agitated on each rotation of the arm. As the arms 21, 22 advance through the waste material, portions thereof ride up upon the inclined surfaces 37 and then drop off the rear edges of the arms, 50 falling back onto the hearth through the streams of air introduced through apertures 30.

Thus as the arms periodically engage each section of the pile of waste material, the material 55 is agitated vertically somewhat and allowed to fall through streams of heated air to insure a rapid and uniform drying action. At the same time the member 20 is continuously rotating within the middle and deepest portion of the pile of waste material and constantly discharging heated air into all portions thereof through the openings 29 for effecting a preliminary drying. As above indicated, the arms 21, 22 may extend 60 outwardly along axes which are generally tangential in respect to portions of the conical member 20, i. e. the inner ends of the longitudinal axes of these arms are spaced substantially from the vertical axis of the member 20. In such 65 positions the arms upon each revolution will 70 serve to advance portions of the waste material outwardly somewhat, on the hearth area 15 and to an extent such as to gradually feed relatively small portions of the drier material, and as fast as it is dried sufficiently, onto the annular grate 75 area 16.

It will be apparent that the above described arrangement will not only avoid or largely dispense with the necessity for hand-stoking, but also insure uniform drying and gradual advance of the dried material onto the grate areas at a sufficient rate to insure rapid and uniform burning in a manner much more satisfactory than would be achieved with laborious and careful manual stoking. The assembly of the conical member 20 and its arms is such that it will be 10 in general, uniformly covered by the pile of material 19, and the member 20 is of such shape as to properly and uniformly distribute drying air to the deepest portions of the pile and to cause such portions interiorly of the pile to slide 15 downwardly and outwardly into the path of the arms as the material becomes more dried and as the arms advance the driest material onto the grate.

The rotating assembly comprised in the conical member 20 and the arms 21, 22, as is apparent from the drawings, may be of an exceedingly durable construction free of irregularly protruding parts and therefore avoiding any possibility that the rotating parts would become 20 25 tangled in the irregular waste material.

The alternative form of structure shown in Figs. 7-9 inclusive, may be constructed and operated in accordance with the same general principles as the construction above described, and corresponding parts are identified by the same reference numerals accompanied by prime marks. However, in Figs. 7-9 the conical portion 20' may be constructed as a part separate from a cylindrical base portion therefor as at 40, the portions 20' and 40 having a suitable flanged engagement as at 41 along the annular line of juncture of these two parts. The member 40 may have at its base an inwardly extending annular flange 42 suitably secured to a flange 43 30 35 at the upper interior portion of member 23'. The upper outer edge of the member 23' may be formed with an annular portion 44 extending up above the surface of hearth 15 and into an annular cavity 45 formed in the member 40. The lower rim of the member 40 may have an 40 45 overhanging portion as at 46. The construction of the parts 44, 45, 46 is thus such as to prevent the waste material from entering the regions of the bearings within the member 23'.

The construction of the members 20', 40 and 23' as separate parts, facilitates manufacture of the castings and also enables ready repair or replacement of any of these parts which may become worn or broken without the necessity of 50 55 replacing or renewing the others.

As shown in Figs. 7, 8 and 9, the cross-sectional outline of the arms 21', 22' may be such that the arms are formed with upwardly diverging upper and lower surfaces connected at the rear portion of the arms by a portion of smooth arcuate cross section as at 47, 48, with the radius of the arc decreasing gradually at the outer portions of the arms. In this embodiment the air discharge apertures 30' in the arms may be located in the under surfaces of the arms and thus at points where there will be no danger of the waste material falling into these openings and causing stoppage thereof.

In Figs. 7-9 the bolts 35', instead of engaging 70 a slot as in Fig. 6, may be provided with notched cleat-like washer members as at 49 (Fig. 8) for engaging an arcuate flange 36' formed on the periphery of the sector-shaped flange portion 33'. As shown, the flange portion 36' and the members 75

49 may have a hook-like clamping engagement, whereby when the bolts 35' are loosened, the angular positions of the arms on their longitudinal axes may be readily adjusted and when the bolts 5 34', 35' are tightened, the arms will be firmly secured and substantially sealed in respect to the member 40.

By removing the conical member 20', access may be had to the interior of its base member 40, 10 as well as to the interior of the member 23' and the cavities within the arms, thus facilitating 15 cleaning of the interior of these various parts.

While the invention has been described in detail with respect to a particular preferred example, it will be understood by those skilled in the art after understanding the invention that various changes and modifications may be made without departing from the spirit and scope of the invention, and it is intended therefore in the 20 appended claims to cover all such changes and modifications.

What is claimed as new and desired to be secured by Letters Patent is:

1. Incinerating apparatus comprising a furnace chamber, the central floor area of said chamber comprising a substantially horizontal and circular stationary hearth, an annular grate surrounding said hearth as a generally horizontal continuation thereof adjacent the side walls of the chamber, a generally conical member upstanding from the mid-portion of said hearth and having air discharge openings distributed over its surface, an opening into the upper part of said chamber for introducing material to be burned to form a pile over said member, means beneath said chamber for rotating said member, one or more arms mounted on said member and extending generally tangentially therefrom, outwardly over said hearth for gradually advancing said material over said hearth and onto said grate,

and means for supplying air to the interior of said member, whereby the material is dried in such pile, while being agitated by said arm or arms and gradually advanced while drying, over said hearth, and onto said grate for burning. 5

2. Apparatus for agitating and advancing waste material outwardly of a generally circular hearth, comprising an arm extending substantially parallel to the hearth surface, means for supporting said arm and rotating same about a 10 vertical axis spaced from the inner end of the arm, the advancing edge of said arm having a cross-section forming an acute angle directed downwardly and forwardly, and means for adjustably securing said arm to its support, the latter means being constructed and arranged to permit turning the arm about a longitudinal axis to vary the angular position of the advancing surface of the arm in respect to the hearth. 15

3. Incinerating apparatus for drying and burning waste material comprising a furnace chamber, the central floor area of said chamber being substantially horizontal and comprising a circular stationary and substantially imperforate 25 hearth, an annular grate area surrounding said hearth, said hearth and grate areas respectively being constructed and arranged for drying and then burning the waste material, means for discharging air into a pile of the material on said 30 hearth, including an upstanding rotatable hollow member mounted at the central portion of said hearth and having air discharge openings in its surface, and means extending adjacent said hearth, generally outwardly and non-radially 35 from said member and rotatable therewith for advancing the lowermost and dried material of said pile gradually outwardly of said hearth onto said grate area. 40

CHARLES W. NICHOLS. 40
